(57) **CLAIM**

The ornamental design for an electrode array as shown and described.

DESCRIPTION

FIG. 1 is a perspective view of an electrode array in accordance with a first embodiment of our design;

FIG. 2 is a top plan view of the electrode array of FIG. 1; FIG. 3 is a bottom plan view of the electrode array of FIG. 1;

FIG. 4 is a left side elevational view of the electrode array of FIG. 1;

FIG. 5 is a right side elevational view of the electrode array of FIG. 1;

FIG. 6 is a rear elevational view of the electrode array of FIG. 1;

FIG. 7 is a front elevational view of the electrode array of FIG. 1;

FIG. 8 is a perspective view of an electrode array in accordance with a second embodiment of our design;

FIG. 9 is a top plan view of the electrode array of FIG. 8; FIG. 10 is a bottom plan view of the electrode array of FIG. 8;

FIG. 11 is a left side elevational view of the electrode array of FIG. 8;

FIG. 12 is a right side elevational view of the electrode array of FIG. 8;

FIG. 13 is a rear elevational view of the electrode array of FIG. 8;

FIG. 14 is a front elevational view of the electrode array of FIG. 8;

FIG. 15 is a perspective view of an electrode array in accordance with a third embodiment of our design;

FIG. 16 is a top plan view of the electrode array of FIG. 15; FIG. 17 is a bottom plan view of the electrode array of FIG. 15;

FIG. 18 is a left side elevational view of the electrode array of FIG. 15;

(Continued)

FIG. 19 is a right side elevational view of the electrode array of FIG. 15;
 FIG. 20 is a rear elevational view of the electrode array of FIG. 15; and,
 FIG. 21 is a front elevational view of the electrode array of FIG. 15.

The broken lines having consistent dash lengths (dash-dash-dash) represent portions of the medical treatment apparatus that form no part of the claimed design.

In FIGS. 1-5, 8-12, and, the broken lines having inconsistent dash lengths (short dash-medium dash-short dash) define boundaries of the claimed design and form no part thereof. Similarly, the line segments in FIGS. 15-19 extending transversely across the electrode array between the portions of the electrode array shown in solid lines and the portions of the electrode array shown in broken lines define boundaries of the claimed design and form no part thereof. There are symbolic breaks along the lengths of the medical treatment apparatus in FIGS. 1-5, and 8-12. In these figures, the break lines and the open spaces between the break lines indicate indefinite length and form no part of the claimed design.

1 Claim, 15 Drawing Sheets
